UNITED STATES PATENT OFFICE

112,413

DESIGN FOR A HAT

Knute Schanzer, New York, N. Y.

Application September 8, 1938, Serial No. 79,773

Term of patent 3½ years

To all whom it may concern:

Be it known that I, Knute Schanzer, a citizen of the United States and residing in Manhattan, in the city, county, and State of New York, have invented a new, original, and ornamental Design for a Hat, of which the following is a specification, reference being had to the accompanying drawing, forming part thereof, wherein

Fig. 1 is the front view of a hat showing my new design.

Fig. 2 is a side view thereof.

Fig. 3 is a rear view of Fig. 1.

I claim:

The ornamental design for a hat, substantially as shown.

KNUTE SCHANZER.
